UNITED STATES PATENT OFFICE

RALPH C. SMITH, OF LOS ANGELES, CALIFORNIA

DESIGN FOR A CASING FOR A GOLF BALL PAINTING MACHINE

Application filed February 13, 1931. Serial No. 38,638. Term of patent 14 years.

To all whom it may concern:

Be it known that I, RALPH C. SMITH, a citizen of the United States, residing at Los Angeles, in the county of Los Angeles and State of California, have invented a new, original, and ornamental Design for Casing for a Golf Ball Painting Machine, of which the following is a specification, reference being had to the accompanying drawings, forming a part thereof.

Fig. 1 is a front elevation of the casing, showing my new design.

Fig. 2 is a top plan view thereof.

I claim:

The ornamental design for a casing for a golf ball painting machine substantially as shown.

R. C. SMITH.
